UNITED STATES PATENT OFFICE.

CHARLES SAMUEL FRANKLIN, OF BUCKHURST HILL, AND PETER PENDLETON ECKERSLEY, OF WITHAM, ENGLAND, ASSIGNEES TO RADIO CORPORATION OF AMERICA, A CORPORATION OF DELAWARE.

WIRELESS SIGNALING.

Application filed May 17, 1922, Serial No. 561,558, and in Great Britain May 25, 1921.

According to our invention we construct an aerial system which has a common part and two branches connected to and preferably connecting this common part to earth, 5 the time period of the first branch being equal or approximately so to that of the common part, while the second branch has a different time period, in other words the second branch is connected to the combination 10 of the common part and the first branch at or near to a node of potential, so that the introduction of this second branch will not affect the tune of the combination of the common part and the first branch. To this 15 combination we couple a circuit in which oscillations can be generated for transmission. This will result in relatively small currents of the transmitted wave length flowing in the second branch. If therefore, 20 waves of a length corresponding to the tune of the combination of the common part and the second branch be emitted from a distant station, such waves falling upon the system will cause beat currents to be set up in the 25 second branch. To this second branch therefore we couple a circuit in which the beat currents can be rectified and passed to a circuit tuned to the beat frequency which may be widely different from that of the 30 transmitted frequency, so that any oscillations which may be set up in this last mentioned circuit from the local transmitter will be very feeble and will not affect the reception of signals from the distant station. 35 Our invention is illustrated by the accompanying diagram.

The aerial system has a common part L_c and two branches containing capacities and inductances L_t , C_t , and L_r , C_r . We adjust 40 the value of L_t , C_t , so that the branch L_t , C_t , is in resonance with the common part. Thus when currents of the frequency N_t , to which the common part and the branch L_t , C_t , are tuned, are induced into the aerial 45 A by a circuit T , the point O becomes nearly a node of potential and nearly all such currents flow in the path L_t , C_t . Thus we make the aerial system with L_c , L_t , C_t , our transmitting radiation system and comparatively large currents are caused to flow 50 therein.

By suitably choosing the values of L_r , C_r ,

the aerial system is given another period tuned to the wave length to be received and a large part of the received currents is confined to the path L_r , C_r . 55

Owing, however, to the resistance of the path L_t , C_t , some of the currents of the transmitted frequency N_t , will flow in L_r , C_r . 60

The intensity of the currents set up in the aerial L_c , L_t , C_t , is very great compared to the received oscillations, but the intensity of the currents that leak into the path L_r , C_r , are, due to the point O being nearly nodal 65 to the frequency N_t , commensurate with the received oscillations.

Thus in the path L_r , C_r , there are set up two commensurate oscillations of frequency N_t , and N_r , the latter being the frequency 70 of the received waves.

These oscillations beat together and produce in the close coupled circuit L C , which is tuned to the frequency N_r , a frequency 75

$$Nb = \pm N_t \mp N_r.$$

By rectifying these beats suitably by a three electrode valve V or other rectifying device, a circuit L_b C_b tuned to a frequency N_b can be set into oscillation. 80

An amplifier can then be associated with L_b , C_b , to amplify these beats and manifestly can be arranged to amplify at a frequency far removed from that of the powerful transmitting currents, and can therefore 85 function efficiently without interference from such currents.

The most difficult problem is to prevent the oscillatory currents of frequency N_t which leak into L_r , C_r , from being too 90 powerful and so swamping the valve V .

The inductance L_t must therefore be made of a resistance as low as possible.

In some cases we may arrange for a negative potential to be established between the 95 grid and filament of the valve V by means of potentiometer P .

We have found it advisable to use coupled circuits at L_b , C_b , in order to prevent direct wipe out of the amplifier due to the 100 currents of frequency N_t flowing in L_r , C_r .

We have found it advantageous sometimes to arrange mutual couplings between the two paths L_r , C_r , and L_t , C_t , so as to balance

out too great a leakage of transmitted currents into the receiving branch $L_r, Cr.$

Having described our invention, what we claim is:

5. In signaling systems, a transmitting-receiving circuit comprising a common portion and a pair of mutually coupled branches connected to said common portion, said common portion and one of said branches being 70
10 adjusted to be resonantly responsive to oscillations of a predetermined frequency, and said common portion and the other branch being adjusted to be resonantly responsive to oscillations of a different frequency, and 75
15 a circuit coupled to one of said branches and comprising a portion resonantly responsive to oscillations of a frequency equal to the difference between said first two frequencies. 80
2. In signaling systems, a transmitting-receiving circuit comprising a common portion and a pair of mutually coupled branches connected to said common portion, said common portion and one of said branches being 85
20 adjusted to be resonantly responsive to oscillations of a predetermined frequency, and said common portion and said other branch being adjusted to be resonantly responsive to oscillations of a different frequency, means for generating in said common portion 90
25 and one of said branches oscillations of the frequency to which said common portion and said branch are responsive, and a circuit coupled to the other of said branches and comprising a portion resonantly responsive to oscillations of a frequency equal to the difference between said first two frequencies. 95
3. In signaling systems, a transmitting-receiving circuit comprising a common portion 100
40 and a pair of mutually coupled branches connected to said common portion, said common portion and one of said branches being adjusted to be resonantly responsive to oscillations of a predetermined frequency, and 105
45 said common portion and said other branch being adjusted to be resonantly responsive to oscillations of a different frequency, means for generating in said common portion and one of said branches oscillations 110
50 of the frequency to which said common portion and said branch are responsive, and a circuit coupled to the other of said branches and comprising coupling means and a portion resonantly responsive to oscillations of a frequency equal to the difference between 115
55 said first two frequencies, and a rectifier interposed between said coupling means and said last named portion. 120
4. In signaling systems, a transmitting-receiving circuit comprising a common portion 125
60 and a pair of mutually coupled branches connected to said common portion, said common portion and one of said branches being adjusted to be resonantly responsive to oscillations of a predetermined frequency, and 130
5. In a signaling system, a transmitting-receiving circuit comprising a common portion and two mutually coupled branches connected thereto, said common portion and one of said branches being tuned to a predetermined frequency, said common portion and the other of said branches being tuned to a predetermined different frequency, means for supplying to one of said branches oscillations of a frequency adapted to beat with oscillations of the frequency to which said branch is tuned, an additional circuit coupled to said branch and comprising a detector and means for selectively amplifying oscillations of beat frequency. 95
6. In a signaling system, a transmitting-receiving circuit comprising a common portion and a pair of mutually coupled branches connected to said common portion, said common portion and one of said branches being tuned to a predetermined frequency, said common portion and said other branch being tuned to a predetermined different frequency, means associated with one of said branches for producing in said branch oscillations of a frequency to which said branch is tuned, a circuit coupled to the other of said branches and comprising a detector and means for selectively amplifying oscillations of a frequency equal to the difference between the first two named frequencies. 100
7. In a signaling system, a transmitting-receiving circuit comprising a common portion and a pair of branches connected to said common portion, said common portion and one of said branches being tuned to a predetermined frequency, said common portion and said other branch being tuned to a predetermined different frequency, means associated with one of said branches for producing in said branch oscillations of a frequency to which said branch is tuned, a circuit coupled to the other of said branches and comprising a detector and means for selectively amplifying oscillations of a frequency equal to the difference between the first two named frequencies. 110
8. In a signaling system, a transmitting-receiving circuit comprising a common portion and a pair of branches connected to said common portion, said common portion and one of said branches being tuned to a predetermined frequency, said common portion and said other branch being tuned to a predetermined different frequency, means associated with one of said branches for producing in said branch oscillations of a frequency to which said branch is tuned, a circuit coupled to the other of said branches and comprising a detector and means for selectively amplifying oscillations of a frequency equal to the difference between the first two frequencies, and means for varying the coupling between said branches independently of variations in tuning. 115
9. In a signaling system, a transmitting-receiving circuit comprising a common portion and a pair of branches connected to said common portion, said common portion and one of said branches being tuned to a predetermined frequency, said common portion and said other branch being tuned to a predetermined different frequency, means associated with one of said branches for producing in said branch oscillations of a frequency to which said branch is tuned, a circuit coupled to the other of said branches and comprising a detector and means for selectively amplifying oscillations of a frequency equal to the difference between the first two frequencies, and means for varying the coupling between said branches independently of variations in tuning. 120
10. In a signaling system, a transmitting-receiving circuit comprising a common portion and a pair of branches connected to said common portion, said common portion and one of said branches being tuned to a predetermined frequency, said common portion and said other branch being tuned to a predetermined different frequency, means associated with one of said branches for producing in said branch oscillations of a frequency to which said branch is tuned, a circuit coupled to the other of said branches and comprising a detector and means for selectively amplifying oscillations of a frequency equal to the difference between the first two frequencies, and means for varying the coupling between said branches independently of variations in tuning. 125
11. In a signaling system, a transmitting-receiving circuit comprising a common portion and a pair of branches connected to said common portion, said common portion and one of said branches being tuned to a predetermined frequency, said common portion and said other branch being tuned to a predetermined different frequency, means associated with one of said branches for producing in said branch oscillations of a frequency to which said branch is tuned, a circuit coupled to the other of said branches and comprising a detector and means for selectively amplifying oscillations of a frequency equal to the difference between the first two frequencies, and means for varying the coupling between said branches independently of variations in tuning. 130

receiving circuit comprising a common portion and a pair of branches connected to said common portion, said common portion and one of said branches being tuned to a 5 predetermined frequency, said common portion and said other branch being tuned to a predetermined different frequency, means associated with one of said branches for producing in said branch oscillations of the 10 frequency to which said branch is tuned, a circuit coupled to the other of said branches and comprising a detector and means for selectively amplifying oscillations of a frequency equal to the difference between the 15 first two frequencies, and means independent of tuning for controlling the amount of current of the first mentioned frequency flowing in said last mentioned branch.

9. In a signaling system, a transmitting-
20 receiving circuit comprising a common portion and a pair of branches connected to

said common portion, said common portion and one of said branches being tuned to a predetermined frequency, said common portion and said other branch being tuned to a 25 predetermined different frequency, means associated with one of said branches for producing in said branch signaling oscillations of the frequency to which said branch is tuned, a receiving circuit coupled to the other of said branches and comprising a detector, and means for selectively amplifying oscillations of a frequency equal to the difference between the first two frequencies, and means for permitting a predetermined 30 amount of oscillatory current of signaling frequency to flow in the second branch to produce beats with oscillatory currents of the frequency to which said branch is tuned. 35
